UNITED STATES PATENT OFFICE.

JOHN F. NETTLE, OF BUTTE, MONTANA.

RESILIENT WHEEL.

1,136,704.

Specification of Letters Patent. Patented Apr. 20, 1915.

Application filed November 7, 1913. Serial No. 799,684.

To all whom it may concern:

Be it known that I, JOHN F. NETTLE, a citizen of the United States, and a resident of Butte, in the county of Silverbow and State of Montana, have invented a new and Improved Resilient Wheel, of which the following is a full, clear, and exact description.

This invention relates to improvements in resilient wheels, and has for an object to provide an improved structure wherein the resilient effect of a pneumatic cushion is provided without liability of puncturing of the cushion.

Another object of the invention is to provide a wheel having a felly formed with bores in which a pneumatic cushioning member is arranged, and which is adapted also to accommodate a reciprocating member formed with a contact shoe at the outer end, whereby the wheel is given a proper resilient effect without subjecting the pneumatic balls to the earth.

In carrying out the object of the invention a wheel structure is provided formed with a felly of special construction. This felly is provided with a plurality of bores on the periphery, the bores preferably extending at a tangent and designed to receive a cushioning member, as for instance a pneumatic ball, and also the end of a reciprocating shoe, whereby the shoe is resiliently supported when the wheel is in use. A pair of side plates are provided for properly holding the shoe in place, and also the various balls so that there will be no movement of the respective parts except a proper reciprocation of the shoes.

In the accompanying drawing—Figure 1 is a side view of a wheel embodying the invention, certain parts being broken away for better illustrating the construction; Fig. 2 is a section through Fig. 1 approximately on line 2—2; Fig. 3 is a view similar to Fig. 2, but disclosing a slightly modified form of the invention.

Referring to the accompanying drawing by numeral 1 indicates a hub, and 2, spokes connected therewith, and also with felly 3. The felly 3 is of special construction. Connected with felly 3 are side plates 4 and 5 held against separation at the periphery by suitable bolts 6. Arranged in felly 3 are a

plurality of bores 7 extending at a tangent, said bores extending from the periphery of the felly inwardly, and each pair having arranged therein a pneumatic cushion 8 in the form of a ball. The ball of course is hollow, and may be supplied with air or gas of any desired kind without departing from the spirit of the invention. Resting on the respective balls 8 are reciprocating members 9 provided at their outer ends with feet 10, the outer face of the feet 10 being struck on the arc of a circle so that all of the feet taken together form substantially a continuous surface, as shown in Fig. 1. The body of each of the reciprocating members 9 is formed with shoulders 11 designed to rest against retaining straps 12 secured to the felly in any desired manner. The extreme outer edges of the side plates 4 and 5 are bent over at 13 and 14 for engaging the shoulders 11, as clearly shown in Fig. 2. By this structure the reciprocating members 9 may be moved inwardly when in the position shown in Fig. 1, but cannot move outwardly from such position. When the wheel is in use these members will successively move inwardly and collapse to a greater or less extent, the balls 8. As soon as the wheel is turned over so that the respective reciprocating members are released the cushioning members 8 move the members 9 back to the position shown in Fig. 1.

In Fig. 3 will be seen a slightly modified form of the invention in which balls 15 and 16 are arranged in each of the bores 7' whereby a greater cushioning effect is produced for the reciprocating member 9'.

What I claim is—

In a resilient wheel of the character described, a felly formed with a plurality of bores arranged at a tangent, each bore having an appreciable depth and having straight side walls, a pneumatic ball in each of said bores, a plunger arranged in each of said bores and resting against said balls, each of said plungers being formed with bearing sides engaging the side walls of said bores so as to be guided in a reciprocatory movement thereby, each of said plungers being also formed with shouldered portions, a pair of side plates rigidly secured to said felly, said side plates being formed with over-

hanging peripheral edges engaging certain of said shoulders, and a retaining plate arranged between respective plungers overhanging other of said shoulders, whereby the 5 plungers are limited in their outward movement.

In testimony whereof I have signed my

name to this specification in the presence of two subscribing witnesses.

JOHN F. NETTLE.
